UNITED STATES PATENT OFFICE.

JOHN M. HANNON, OF HARTFORD, CONNECTICUT.

RAILWAY-TRAIN STOP.

1,178,238.

Specification of Letters Patent.

Patented Apr. 4, 1916.

Application filed May 1, 1914. Serial No. 835,726.

To all whom it may concern:

Be it known that I, JOHN M. HANNON, a citizen of the United States of America, and resident of Hartford, in the county of 5 Hartford and State of Connecticut, have invented certain new and useful Improvements in Railway-Train Stops, of which the following is a full, clear, and exact description.

10 This invention relates to means for the stopping of a railway train which may run past a signal or into a block while another train is in the same block, and which is automatically operative in cases where the 15 engineer from carelessness or disability does not properly check or stop the train.

The invention includes the combination with a locomotive, a trackway on which it runs, a means, such as the throttle valve operating lever for controlling the running of the locomotive, of a helically grooved rotative member with which said controlling means engages, a compressed air or other motor to operate said grooved member and 25 which has a controller, mechanism on a locomotive extending from adjacent the trackway to the motor controller for operating the latter, and means at intervals (such as the distance between the blocks) along 30 the trackway for actuating the last named mechanism.

The invention is described in conjunction with the accompanying drawings and is set forth in the claims.

35 In the drawings:—Figure 1 is a side elevation of a locomotive with the apparatus of the present invention indicated as applied thereon. Fig. 2 is a partial plan view showing parts of the apparatus located in 40 the cab. Fig. 3 is a plan view, and Fig. 4 is an elevation showing the throttle valve operating lever and devices directly coöperative therewith. Fig. 5 is a side elevation showing parts in detail to be hereinafter referred to. Fig. 6 is a plan view, and Fig. 45 7 is a side elevation indicating the supplemental or third rail and parts in this invention carried by the locomotive truck coacting with said supplemental rail.

50 In the drawings, A represents the stem of the throttle valve to which the throttle lever B is connected as usual, said throttle lever being pivoted at a to a bracket or support therefor. The throttle lever has its portion toward its connection with the throttle valve stem made in the form of a

yoke as represented at b, said yoke having an embracing relation to a rotatable member, C, which has the contour thereof curved from end to end on an arc generated from 60 the pivot a; and the so shaped member, C, has a comparatively deep helical groove, e, extending from end to end thereof. On the outer barlike portion of the throttle valve lever is a slidable member, D, having a 65 tooth, f, for engagement in the groove, e. The slidable member is by link g connected with a short arm, g² of the stem, g³ of a hand wheel, g⁴ which is rotatably carried on the outer end of the throttle lever, B, so 70 that by the rotation of the hand wheel the slidable member, D, may have the tooth f thereof disengaged from and reengaged with the helical groove, e, of the rotatable member, C. The said rotatable member has 75 the shaft C² thereof in connection with a motor, here conventionally represented by F and understood in the present instance as being an air motor of a common type and operated by compressed air, supplied 80 from a suitable source by the pipe F². This pipe has a valve, h—i representing the stem thereof,—on which a lever, j, is affixed. Coacting with the air valve lever, j, is a slide rod, K, ranging longitudinally of the 85 locomotive, and having at its rear end an offset, or shoulder, k, located for engagement with the air valve lever, j.

On the truck, K, comprising the small wheels of the locomotive is pivotally connected a frame, J, which may swing vertically; and this frame carries a wheel or roller, L, which runs along the supplemental rail, M, which is between the usual track rails, N N, and which supplemental 95 rail is made with an inequality, m, as represented in Fig. 7. Pivotally hung from the locomotive body, at the part Q of the latter which is supported on the truck, K, is another vertically swinging frame or 100 yoke, P, a part of which rests on the roller frame, J.

o represents an angle lever pivotally mounted at its elbow on the body of the locomotive and to the upper end of which the 105 aforementioned slide bar, L, is connected, while the other arm of said angle lever is by link o² pivotally connected to the springing frame, P, which is hung from the locomotive body independently of the roller 110 carrying frame, which is hung from the truck.

The frame J may swing transversely in unison with the truck, K, as in the rounding of curves, etc., but by the provision of the supplemental frame, P, hung from the locomotive body, such frame and its connections with the slide bar do not partake of any of the swinging or transverse movements of the truck, and are not distorted by the movement of the truck.

10 In the running of the train under the careful driving of the engineer, he will upon coming into a block or wherever a signal is set for safety or to proceed, through the hand wheel, g^4 , momentarily disconnect the throttle lever catch from the helically grooved rotatable member, C, thereby insuring the retention of the throttle valve in the open position in which it may have been set; and the arrangements represented in Figs. 3 and 4 are such as to permit the engineer to swing the throttle valve lever to more or less fully open or close the throttle valve. Assuming, however, that the locomotive reaches a place in the trackway 25 where the inequality, m , in the supplemental rail is present, and the engineer is not attentive to the signals, the valve, h , of the air motor pipe will be automatically opened, the helically grooved member, C, will acquire rotation thereby endwise forcing catch tooth, f , of the slide member of the throttle lever, and the latter will be swung on its pivot, a , to fully close the throttle valve for effecting cessation of the driving power of the locomotive. The engineer may restore the running conditions by the outward withdrawal of the slide catch, opening the throttle valve, whereupon the catch will be again placed in engagement with the 30 grooved member, C. At the proper time, after the mechanism has automatically operated, as explained, the engineer will manually close the air motor valve through the medium of the handle j^2 made as an extension of the lever, j . The slide bar, L, may 35 also have connection with the ordinary or any air brake valve, so that in addition to the au-

tomatic closing of the throttle valve, the air brakes may be set for the more immediate stopping of the train. It is noted that the 50 helically grooved rotatable member C is provided at the outer end of the spindle C^2 with a hand wheel C^3 which permits the engineer to impart rotative movement to the 55 said member C and thereby adjust the throttle valve in its more or less opened condition as may be desired, and which might not in all cases be possible through the 60 throttle lever when account is taken that the pitch of the helical groove is comparatively steep.

I claim:

1. The combination with the throttle valve lever of a locomotive, of a rotative helically grooved member with which the said 65 lever engages, a swinging roller-provided frame carried by the locomotive, a fluid actuated motor operable to rotate said helically grooved member having a controlling valve therefor, and means operated by the 70 said roller carrying frame for opening said motor controlling valve.

2. The combination with the throttle operating lever of a locomotive provided with a slide catch and means for operating 75 such catch, of a helically grooved rotatable member with which said catch engages and an air motor in driving connection with said grooved member having a valve and an operating lever arm therefor, a slide bar 80 having a shoulder coacting with said lever arm, an angle lever having one arm thereof connected to said bar, a swinging frame mounted on the locomotive and having a link connection with the other arm of said 85 angle lever and means for imparting a swinging motion to the said frame.

Signed by me at Springfield, Mass., in presence of two subscribing witnesses.

JOHN M. HANNON.
